UNITED STATES PATENT OFFICE.

HENRY G. DAVIS, OF NEW YORK, N. Y.

IMPROVEMENT IN CRUTCHES.

Specification forming part of Letters Patent No. 37,387, dated January 13, 1863.

To all whom it may concern:

Be it known that I, HENRY G. DAVIS, M. D., of New York, in the city and county of New York, have invented a certain new and useful Improvement in Crutches; and I do hereby declare that the following specification, taken in connection with the accompanying drawings, is a full and exact description thereof, which I have prepared for the purpose of procuring Letters Patent therefor.

My improvement relates to the construction and arrangement of the handle relatively to the crutch. It is attached to a thimble capable of an adjustment vertically upon the staff of the crutch, and is so arranged that it stands on the outer side, out of the line of the crutch, and always coincides with the chord of a circle perpendicular to and concentric with the axis of the crutch. By this construction and arrangement of the handle I obtain the following advantages:

First. An adjustable handle which may be regulated to suit the height of the patient, or to bring the arm to the most easy and comfortable position. This position can only be found by trial in each individual case, and may require to be altered several times before the proper place for the handle is found.

Second. From the position of the handle the natural downward and inward pressure of the hand is brought to bear more nearly upon the base of the crutch, and, consequently, there is a much lessened or no pressure upon the sides of the axilla. The direction of this force is represented by the red line in Figure 1, and the effect of reducing the pressure upon the side of the body is very important. As ordinarily constructed, the crutch bears with considerable force against the body, creating not only an unpleasant pressure, but interfering to a serious degree with the flow of blood through the axillary artery and veins. I have found in my practice that even children quickly perceive the greater ease and comfort of my improved crutch over those heretofore known and invariably prefer it.

Third. Great simplicity and cheapness of construction as compared with the approved forms of crutch heretofore known.

In the drawings, Fig. 1 represents my im-

proved crutch in use with a portion of the body of the patient in outline. The red line indicates the direction of the force ordinarily exerted by the arm upon the handle. Fig. 2 is a cross section showing the handle in plan on a larger scale, and Fig. 3 is a side elevation of the handle on the same scale as Fig. 2.

A is the staff of the crutch, which is a single cylindrical or slightly-tapering rod. B is the head of the ordinary form and construction. C is a ferrule or thimble to slide upon the staff, and provided with a screw, c, holding it in place. From each side of this ferrule curved arms D extend, as shown in Fig. 3, and upon the ends thereof is fastened a cylindrical handle, E, by screws e, as represented. The construction of these parts is so plainly shown in the drawings as to be evident to those skilled in the art. The proportions shown are those I have found to work well in practice, but they may be varied within certain limits without affecting the character of the invention. The distance of the handle E from the staff A should be such that the line of pressure of the hand shall intersect the axis of the crutch at or near the lower end thereof, as indicated by the red line. In the ordinary crutch this line intersects the axis of the staff at the handle, thus causing a considerable side strain against the body with the evil effects alluded to above. If it intersects at or near the lower end, as represented, there is little or no such side strain felt at the top, and the crutch is rendered much more comfortable and less liable to interfere with the proper circulation of the blood.

Having now fully described my said invention, what I claim as new therein, and desire to secure by Letters Patent, is—

An adjustable handle, E, constructed and arranged to serve in connection with the staff, as and so as to realize the advantages herein set forth.

In testimony whereof I have hereunto set my name in presence of the subscribing witnesses.

HENRY G. DAVIS.
